FUEL-OIL SUPPLY SYSTEM

John Leonard Taylor, Milwaukee, Wis.

Application September 26, 1931, Serial No. 565,282

7 Claims. (Cl. 123—139)

This invention relates to improvements in fluid supply systems and particularly to such as are applicable to supply fluid fuel to internal combustion engines of the Diesel or other types.

5 An object of the invention is to selectively control and vary the volume and pressure of the oil supplied a fuel distributing conduit manually or automatically.

10 A further object is to assure an accurate and complete fuel charge for each fuel-oil injection through an injection pump, whose rate of displacement is less than the rate of fuel injection during the injection time period.

15 Other objects are to provide an injecting pump means that will require a comparatively low total cam-pressure for delivering a relatively large quantity of fuel-oil to an atomizer nozzle during and within the fuel-oil atomizing time period; to individually control the supply of fuel-oil advanced to atomizer nozzles through their respective fuel pumps, and to supply the nozzles with a fuel-oil medium by dependently acting pumps and accumulators; the attaining of a variable delivery of fuel-oil through the use of a fixed stroke injection pump and a resiliently urged accumulator; 20 to predetermine the supply of fuel-oil, during periods when an engine governor is not functioning, or upon other occasions, independently of the governor.

25 A further object is to provide for manual control of a fuel supply to an engine nozzle independently of a governor.

30 Further objects are to provide means to safeguard an engine against excessive speed during such manual control; to provide for instantly stopping an engine supplied by such a fuel system; to provide for individual adjustment of a plurality of injection pumps to obtain proper distribution of fluid supplied through a restricting throttle; and to provide facilities for automatically withdrawing from the fuel medium, air, 35 foamy-oil, or other undesirable matter.

35 A further object is to generally improve the construction and operation of systems of the class disclosed, and further objects and advantages will appear as the specification proceeds.

40 The recited objects are achieved through the novel arrangement of structure described in the following specification, particularly pointed out in the appended claims, and illustrated in the accompanying drawings; the latter being indexed as follows:—

45 Fig. 1 is a sectional elevation of a piston valve assembly including a fragment of its associated governor means.

50 Fig. 2 is a top plan view of the mechanism shown in Fig. 1.

55 Fig. 3 is a vertical sectional view through the head of a fuel injecting pump and associated valve parts.

Fig. 4 is a sectional view on line 4—4 of Fig. 3.

Fig. 5 is a sectional view of an end portion of a fuel distributing conduit.

Fig. 6 is a section on line 6—6 of Fig. 2.

Fig. 7 is a diagrammatic representation of an engine embodying the invention.

Similar reference characters apply to like parts throughout the several views. The assembled groups are here assumed to be connected up in an approved manner consistent with the efficient handling of fluids under pressure, so that, a detailed recital of elements, such as leak-proofing adjuncts, or threaded connections, packing gaskets, etc., need not be specifically described where such adaptations are readily understood to apply.

It is to be understood that the disclosed structure is intended for use with any fluid to which it is or may be found adaptable, and that, accordingly, wherever the words "oil", "fuel", or "liquid" occur in this specification, they are to be given the broadest interpretation consistent with the prior art.

Referring to the drawings, the character E, Fig. 1 indicates a bracket or similar member, either 30 integral or fixed with a Diesel or similar engine, and extended to offer an annular band-like, or sleeve portion E1, and a table portion E2. The said band portion E1 embraces a slidable spring-casing C having trunnions C1 fixed therewith adjacent the brim of the casing. The said casing is supported by an embracing fork or other suitable movable element F in the present instance offering terminal slots f wherein the aforesaid trunnions find pivotal freedom to provide a 40 mechanism capable of rising and falling movements.

A governor-rod R, Fig. 1 in the present instance axially aligned with the casing C, rigidly attaches to the under face of a disc or plate D, 45 between which disc and the bottom of the casing C is confined in the present instance a spring S coiled about the said governor-rod. The fork F has a hub portion F1 and is fixed with a shaft P, the latter being suitably journaled in suitable 50 bearings, either integral or fixed with the member E as shown. A depending worm-gear segment G is fixed in the present instance with shaft P, for actuating the fork member F as will be described presently.

Above disc D and generally in line with governor rod R is a piston valve assembly supported in the present instance by a bracket B which latter is suitably formed to permit fixing same to the bracket or table portion E2. The said assembly comprises a valve block 1 spacedly positioned above the sleeve E1. The said block 1 has a central bore 2 therein for receiving a reciprocable valve-piston 3 which latter is coupled to the upper face of the disc D. A spring 4 is engaged between a portion of the block 1 and the said disc for assisting in depressing the piston 3, in opposition to above mentioned spring S. The governor, not shown, is connected, in the present instance, to tend to pull the governor rod R downwardly upon increase of engine speed, and any force exerted by spring S opposes this movement. The piston 3 is machined to provide a chamber 5 in the bore 2 for connecting together, or preventing a connected relationship between a fluid conduit 6, leading from a source of fluid under pressure 6a including any suitable or well known tank, pump, and relief-valve, or other suitable combination, as shown in Fig. 7, the details of which form no part of the present invention, and a similar conduit 7, through means of an intervening counterbored groove 8 concentric to the bore 2. Through the aforesaid element 6-8-7, the fuel-oil medium which farther on supplies one or more atomizer nozzles N—N, Fig. 7, common to motor cylinders 8a—8a. The present disclosure concerns elements normally included in a singular or multiple atomizer nozzle assembly, which may occur between the structures of Fig. 1, and a dead-end of the conduit 7 shown in Fig. 5. The structure shown in Fig. 3 would, of course, be repeated at each nozzle N, and the said unit will be understood as being close by or in immediate connection with the assembly illustrated in Fig. 3 by means of above mentioned conduit 7. Owing to the normal running clearance about piston 3, some of the fluid oil will find its way up and down the bore 2 in film-like quantities, and this oil will be collected at annular counterbored grooves 9 and 10 from which the recovered oil will be directed through the tube 11, shown dotted, to any suitable container. The valve-piston 3 terminates with a convex end 3' protruding beyond the block 1 far enough to be affected by a pivoted lever 12, under-cut to offer an inclined wedge-like surface 13, which provides a cam relationship between 3' and 13 for sliding the piston 3 longitudinally when it is desired to shut off the engine, or, graduate the communication between chamber 5 and conduits 6 and 7 which latter lead, respectively, to and from the valve block 1. The pivoting of lever 12 includes a locking-washer w which will frictionally arrest the said lever in any of its radial positions.

Beneath the engine body E is suitably journaled a shaft 14 upon which is fixed a worm 15 in mesh with the segment G. The tooth-angle of these inter-geared parts is such in the present instance that same will remain locked for any position they may assume although any other suitable connection between shaft 14 and fork F is contemplated as equivalent. The opposite end of the shaft 14 carries a hand-wheel 16 fixed therewith and a similarly mounted spur-pinion 17. The hand-wheel may conveniently be graduated to provide indicia alignable with a suitable index or the like which will permit setting the wheel readily for whatever running condition may be desired. The pinion 17 is in mesh with a

suitably guided rack-rod 18 for allowing convenient operative rotation of the shaft 14 from some remote location which convenience is essential in certain installations. Other means of remote control of the wheel 16, and its associated parts are contemplated, the particular remote control structure forming no part of the present invention. It will be readily seen, that, with the elements just set forth the fork F can be rocked to raise or lower the casing C thereby 10 affecting the spring S and its associated parts for varying the load on said spring. This action affects the piston 3 varying the flow of fuel-oil through the distributing conduit 7, increasing the flow if the casing is raised and reducing or 15 shutting off the flow entirely if the casing is lowered. Any desired condition of operation of the engine may accordingly be obtained, or the engine may be stopped, by proper manipulation of the wheel 16. A quick stop of the engine may 20 be had by using handle 12 to force valve 3 down into closed position, and the handle may also be used to limit the maximum opening of the valve by merely adjusting it to suitable intermediate positions. By adjusting spring S for a maximum 25 speed, handle 12 may serve as a hand throttle for manual control of the engine throughout its speed and power range.

In Fig. 3 is shown a valve-set to which is attached a conventional injection pump body 19 within which body reciprocates a piston 20, actuated by suitable engine-driven means 20a. The fluid displacement capacity of the piston 20, during the crankshaft-angle of injection period, in the present instance is less than the fuel-oil volume actually required by the connected atomizer nozzle during the time said atomizer is in operation. The total delivery volume of pump 20 is actually in excess of the amount required by an atomizer, but a portion of the pump's stroke is used up in the extensibility of the pipe line between the pump and nozzle, and in the small amount of compressibility which is possible and which becomes appreciable in liquids when subjected to the extremely high pressures here concerned.

In systems of the present type, there is a short time interval between the building up of pressure at the pump and the building up of a corresponding pressure at the nozzle, this interval or "fuel lag" being due to various factors including those just discussed, and possibly others unknown. It becomes particularly important in an engine operating at high speeds, and may lead for example to developing excessive pressures in the neighborhood of the pump, and also in its operating mechanism, these occurring either before, or during the injection period. An organization is accordingly desirable which, while timing the injection accurately while operating at high speeds, will avoid the development of such excessive pressures, either in the piping, the pump, or its actuating mechanism. This discrepancy in volume is for the purpose of avoiding such excessive pressures and is due to the intentional avoidance of a large area piston having a short stroke and high total cam-pressure, in favor of a small area piston with a long stroke and low total cam-pressure. The insufficiency of pump 19—20 is supplied by an auxiliary pump or accumulator means described later on.

Elements in the aforesaid valve-set include a housing 21 suitably united to the pump body 19 in a fluid tight manner. The said housing is opposingly apertured to accommodate sections of 75

tubing T which form the distributing conduit 7. The lower wall of the conduit 7 in the housing 21, has an opening 22 adapted to be regulated by an adjustable valve 23 whose threaded stem 24 is 5 end-slotted in the present instance to allow for screw-driver adjustment the stem passing through a cup-like closure 25, which latter, in turn, is closed by a gland 26 adapted for compressing any appropriate form of packing X, thus 10 offering a conventional stuffing-box for the adjustable stem 24; the adjusting feature of the stem 24 is, in this instance, a highly important provision which allows separate or independent adjustment of the several pumps to determine 15 independently the amount of fluid delivered to each nozzle. It is thus possible with the single throttling or governing device or valve 1-3 etc., to regulate an engine having a plurality of cylinders such as that diagrammatically indicated in 20 Fig. 7, proper distribution of the throttled supply between the individual cylinders being readily effected through the individual adjustment of the valves 23.

Each pump 19 is provided in the present instance with a pair of check valves 27 and 28 acting in series to prevent flow of fluid from the cylinder 19' back into conduit 7, this arrangement being desirable to effect a satisfactorily tight seal in the face of the extremely high pressures developed. Valve 27 engages a suitable seat disposed about opening 22, while valve 28 engages a seat disposed about a port 29 communicating with openings 30 in a cage member 31 arranged substantially axially of bore 19' and between it 35 and above mentioned opening 22. Valve 27 has a stem suitably guided in cage 31, and valve 28 has a stem suitably guided in a diaphragm 31', having openings 30' for admission of fluid into bore 19'. The valves are continuously urged toward their respective seats by springs 27' and 28', whose resilient properties are predetermined to give desired opening pressures or other characteristics. The valves, together with valve 23, accordingly perform a metering function in addition to their operation as check valves.

The fluid flow during downward movement of piston 20 is indicated by the feathered arrows, the fluid passing through the openings 22, 30, 29 and 30' into the piston bore 19'. A conduit 32 leads 50 fuel-oil from said bore 19' during upward movement of piston 20 to an atomizer nozzle N of suitable or well known type which will be located in the present instance at the end of conduit 32. The flow of fluid through the conduit 32 is increased 55 after the requisite discharge pressure is reached at the nozzle by an accumulator 33, having a piston 34 which is resiliently urged by a spring 35 in one direction but which will yield upon the development of a predetermined suitable injection pressure upon the fuel-oil passing through the conduit 32 in the neighborhood of the pump, this pressure not being reached at the nozzle until an instant later as above explained. The spring 35 is encased within a casing 36, which 60 latter is suitably adjustable, for example by being threaded into the accumulator body 33 to allow for adjusting the tension of the aforesaid spring. The pressure in the pump cannot go materially above that for which the spring 35 is 65 set, and this pressure is sufficient for satisfactory injection, any lag introduced by the action of the accumulator being readily corrected by suitably timing the pump piston 20.

It is of course understood that the complete 70 cycle of the pump and accumulator takes place

very quickly, and that the charge in the accumulator is exhausted during each cycle after the nozzle finally opens, the pressure in the piping and pump then falling below the injection pressure and later to that of the pump suction stroke, 5 since the pump is operated without discharge check valves as is common in devices of this class, the resulting quick drop of pressure after injection preventing any undesirable "dribbling" 10 of fluid into the engine cylinder after the desired injection period.

The terminus or dead-end of the conduit 7 is illustrated in Fig. 5 where means are shown for allowing the escape of air, and other particles likely to follow foamy or aerated fluids, here indicated by the dotted arrows. The dead-end of a final section of tubing T is closed by a combination fitting 37 which provides a bleeder-valve 38 adapted to control an aperture 39 located at a "highpoint" in the conduit 7 where air, etc. ultimately arrives. The valve 38 is kept open so that a negligible quantity of the fuel-oil is purposefully allowed to drip through along with the escaping particles and air. This oil discharge passes through a nipple 40 in which is arranged a sight 25 opening 41 for observation purposes, the said discharge being directed through a pipe 42 to any suitable container, preferably to fuel source 6a.

The mechanism illustrative of the invention above described includes a conventional engine 30 governor whose rod R is shown in the drawings, and the usual supply of fuel-oil 6a under suitable pressure for insuring efficient engine operation. The fuel-oil is introduced through the conduit 6, supplying the movable piston-valve in the block 1 35 where the governor, through the rod R, and valve member 3, controls the volume of fuel passing the valve, and incidentally the fluid pressure passed at this point to the distributing conduit 7. It will be obvious that the governor's force can 40 be modified through the hand-wheel group acting on spring S, or the governor may be temporarily rendered inoperative when desired, as for example in starting the engine. Changing the effective force of spring S will operate to change the engine speed at which the governor and spring S will reach a state of balance or equilibrium, and accordingly result in a new engine speed under 45 governor control. For each injection pump in the system means are provided for individually adjusting and controlling conditions thereat, which comprise the above described metering valve-set illustrated in Fig. 3. This assembly offers a valve 23 which may be adjusted for affecting a particular atomizer nozzle, as above described, and compelling same to perform selectively as conditions may warrant, independently of its companion atomizer nozzles. The valves 27 and 28 co-act to provide an assured check for the fuel fluid in conduit 7 which will be, at times, 50 under a pressure that is less than the force exerted by the springs 27'-28'. The variation in pressure will depend upon the behavior of valve 3 which moves under control of the governor to allow an increase of pressure or a reduction of 55 pressure within the conduit 7 accordingly as more or less fuel is necessary to maintain the desired engine speed. The required pressure to open the valves, 27-28, will always be high enough to maintain conduit 7 completely full of fluid whereby any air, foamy fluid, etc., will course upward and onward, as per dotted arrows, towards the egress provided in the fitting 37. Fluid-oil in conduit 7 will fill all of the chamber L and such chambers as occur below it to an extent depend- 60

ing upon the difference in pressure affecting the valves 27-28 caused by the downward movement of piston 20 and the increment of time during which said difference in pressure is exerted. The 5 cylinder bore 19' is thus filled during each suction stroke to an extent determined by the pressure in conduit 7, the springs 27' and 28' being proportioned to apply a predetermined load or resistance to the valves, and whatever fluid finds its 10 way to bore 19' is expelled by the following discharge stroke of the piston. The volume of fluid in each charge is accordingly dependent upon the pressure in conduit 7, and that, in turn, is dependent upon the degree of opening of valve 1-3. 15 The action of the governor in controlling this valve accordingly keeps the speed of the engine substantially constant.

When it is desirable to change the engine speed, a change in the force of spring S through the 20 manipulation of hand wheel 18 will accomplish this, and if manual, or "non-automatic" control is desired, the force of spring S may be largely increased and the valve controlled by hand lever 12 which will then operate like a hand throttle. 25 Even in this event, however, the governor remains "on guard", as it were, and in the event of excessive engine speed through inattention, failure of load, or the like, may overcome spring S, and throttle the fuel enough to prevent damage to the engine. Spring S may also be adjusted 30 for any desired maximum speed, and hand lever 12 used for obtaining any lesser desired speed. The lever is also available for instantly stopping the engine by cutting off all fuel supply.

35 Accumulator 34 operates to relieve excessive pressure which might otherwise be built up in the pump before the said pressures could be transmitted to the atomizer, and increases the effective delivery volume of the pump after the 40 atomizer opens, permitting the use of a relatively small, long stroke piston, and thus reducing the stresses in its operating mechanism.

Having described the invention what is claimed and desired to be protected by United States Letters Patent is:—

1. In a fuel supply for an internal combustion engine including a source of fuel under pressure, and a plurality of injection pumps the combination of an imperforate conduit connected to supply said pumps from said source, a single throttle interposed in said conduit and arranged to control the flow of fuel to all of said pumps, means for changing the setting of said throttle, and inlet check valves for said pumps having resilient means yieldingly maintaining them in closed position, and arranged to yield only upon the development of a predetermined pressure difference between said conduit and the interior of said pumps.
2. In a fuel supply for an internal combustion engine including a source of fuel under pressure, and a plurality of injection pumps, the combination of an imperforate conduit connected to supply said pumps from said source, a single throttle interposed in said conduit and operative to control the flow of fuel to all of said pumps, means for changing the setting of said throttle, and an inlet check valve for each pump, each check valve having means yieldingly maintaining it in closed position, and arranged to yield only upon the development of a predetermined pressure difference between said conduit and the interior of said pump, and each pump having an additional valve adjustable to restrict the flow into the interior 75 of said pump independently of the above men-

tioned check valves, said additional valves constituting means for insuring the correct distribution of fuel passing said throttle, among the several pumps.

3. In a fuel supply for an internal combustion engine including a source of fuel under pressure, and a plurality of injection pumps, the combination of a conduit connected to supply said pumps from said source, a single throttle interposed in said conduit and operative to control the flow of fuel to all of said pumps, means for changing the setting of said throttle, an inlet valve for each pump, each valve being independently adjustable to restrict the flow of fuel into the interior of its associated pump, said valves constituting means for insuring the correct distribution of fuel passing said throttle among the several pumps.

4. In a fuel supply for an internal combustion engine including a pump cylinder and a fuel injection nozzle the combination of a piston reciprocable in said cylinder, an accumulator cylinder adjacent thereto and in open communication with said pump cylinder, a discharge conduit communicating with both said cylinders and adapted to supply said injection nozzle, a piston reciprocable in said accumulator cylinder, and resilient means urging said accumulator piston in a direction to expel fuel from said cylinder, said means being constituted to yield only in response to pressures sufficient to satisfactorily atomize fuel through said nozzle.

5. In a fuel supply for an internal combustion engine including a source of fuel under pressure and an injection nozzle, the combination of a conduit, an injection pump supplied from said source through said conduit, and having a pump cylinder, a discharge duct leading from said pump and adapted to supply fluid to said injection nozzle, a fuel accumulator adjacent said pump and having a fuel passage in open communication with said pump cylinder and communicating with said discharge duct, said accumulator comprising an expansible chamber including resilient means arranged to resist expansion of said chamber and constituted to yield only upon development of a predetermined pressure in said accumulator suitable for operation of said nozzle.

6. In a fuel supply for an internal combustion engine including a source of fuel under pressure and an injection nozzle, the combination of a conduit, an injection pump supplied from said source through said conduit, and having a pump cylinder, a discharge duct leading from said pump and adapted to supply fluid to said injection nozzle, a fuel accumulator adjacent said pump and having a fuel passage in open communication with said pump cylinder and communicating with said discharge duct, said accumulator comprising an expansible chamber including resilient means arranged to resist expansion of said chamber and constituted to yield only upon development of a predetermined pressure in said accumulator suitable for operation of said nozzle, and a throttle interposed in said conduit and arranged to control the flow of fuel to said pump cylinder.

7. In a fuel supply for a high-speed internal combustion engine including a pump cylinder and a fuel injection nozzle, the combination of a piston reciprocable in said cylinder, an accumulator cylinder adjacent thereto, and in open communication with said pump cylinder, a discharge conduit communicating with both said cylinders and arranged to supply said injection nozzle, and having dimensions productive of a

liquid hammer effect when supplied with liquid in impulses at high speeds, a piston reciprocable in said accumulator cylinder, and resilient means urging said accumulator piston in a direction to expel fuel from said accumulator cylinder, said means being constituted to yield only in response to pressures in said accumulator cylinder above those necessary to satisfactorily atomize fuel through said injection nozzle, but within those which would result in said conduit from said liquid hammer effect, said pump having a bore and

stroke so constituted as to give a rate of displacement less than the rate of injection desired at said nozzle whereby said accumulator may receive a portion of each fuel charge prior to building up of injection pressure at said nozzle, and add said portion to the remaining portion of the charge coming from said pump when requisite pressure is reached at said nozzle and fluid flow commences. 5

JOHN LEONARD TAYLOR. 10
